UNITED STATES PATENT OFFICE.

D. B. TRAVIS, OF LA CROSSE, WISCONSIN.

IMPROVEMENT IN VALVES FOR STEAM-ENGINES.

Specification forming part of Letters Patent No. 43,142, dated June 14, 1864.

To all whom it may concern:

Be it known that I, DAVID B. TRAVIS, of La Crosse, in the county of La Crosse and State of Wisconsin, have invented a new and useful Improvement in Steam-Engines; and I do hereby declare that the following is a full, clear, and exact description thereof, which will enable others skilled in the art to make and use the same, reference being had to the accompanying drawings, forming part of this specification, in which—

Figure 1 is a central longitudinal section of the valve-chest, valves, and valve-seats of an engine illustrating my improvement. Fig. 2 is a plan of the valve-seats and horizontal section of the valves. Fig. 3 is a similar view to Fig. 2, but showing the parts in different positions. Fig. 4 is a plan of the bottom of the valve-chest.

Similar letters of reference indicate like parts.

This invention consists in a novel system of movable valve-seats and stationary and movable ports in combination with slide-valves in a steam-engine, whereby the engine is enabled to be reversed and stopped very quickly and easily.

The invention is applied in connection with two slide-valves, A A, one for effecting the induction and ejection of the steam to and from one end, and the other for effecting the induction and ejection to and from the other end, of the cylinder, the said valves being inclosed within a valve-chest, B, to which the steam is admitted, and the two being connected by a rod, C, and worked by a rod or stem, D, passing through a stuffing-box, E, at one end of the chest. The bottom *a* of the chest is faced flat, and has three ports, *b b' c*, at or near each end. The four ports *b b'* which admit steam to the cylinder, are alike and arranged parallel with each other and between the same parallel lines drawn lengthwise of the face *a*, and are of a width less than half the width of the chest, and arranged on one side of a line drawn longitudinally and centrally upon the face *a*, and the two at each end communicate with a single steam way, *d*, which communicates with their respective end of the cylinder. The two ports *c*, which are for the exhaust, are arranged between the same parallel lines drawn lengthwise upon the seat *a*, and on the opposite side of the central longitudinal line to that on which *b b'* are arranged,

and each is arranged opposite the middle of the space between its respective ports *b b'*, and the two communicate, as shown in dotted lines in Figs. 1, 2, and 4, with a common exhaust-chamber, *e*.

F F are the movable valve-seats, two in number, one for each valve. Each consists of a flat plate of iron faced on both sides and fitted to the face *a*, which may be called the "permanent seat," and fitted to work freely between the sides of the valve-chest or between suitable guides provided therein, and each is made with a stem, *j*, to enable it to be connected with one of the two arms *g g* of a shaft, *G*, which is arranged perpendicular to the seat *a*, and fitted to a bearing in the center of the said seat, and to a stuffing-box, *h*, in the center of the cover *B'* of the valve-chest. The said stems are arranged on opposite sides of the said shaft, and the said arms set in opposite directions, so that by turning the said shaft by means of a lever, *H*, or its equivalent, secured to it outside of the valve-chest, the two seats may be moved in opposite directions both toward or both from the ends of the chest. A pinion may be substituted for the arms *g g* to work in toothed racks on the valve-stems. In each of the movable seats there are three ports, *i i' j*, passing through it. The ports *i i'* are so arranged that they occupy the same space in the width of the valve-chest as the ports *b b'*; but they are about one-third narrower in the direction of the length of the chest, and are set nearer together, the difference being a little more than the width of one of the ports *i i'*, so that when the movable seats are close up to the ends of the valve-chest, as shown in Fig. 3, and the outer edges of the outer ports, *i i*, are in the same vertical lines with the outer edges of the outer ports, *b b'*, the inner ports, *b b*, are effectually closed by the movable seats, and when the said seats are brought to the reverse positions shown in Fig. 1, and in black outline in Fig. 2—that is to say—with the inner edges of the inner ports, *i i*, in the same vertical lines with the inner ports, *b b*—the ports *b b'* are effectually closed by the valve-seats. The exhaust-ports *j* in the movable seats are arranged, like those of *c*, in the permanent seat—that is to say, on the opposite side of the center of the valve and midway between the two ports *i i*; but the exhaust-ports *c* in the permanent seat are made so

much wider than those of *j* in the movable seats that there is always free communication between the said ports *j* and *c*, whatever be the positions of the movable seats. Stops *k* are secured in the permanent seat *a* to prevent the movable seats approaching each other nearer than is necessary to bring the ports *j* to the positions described with reference to Fig. 2.

The valves *A A* are of such area that their exhaust cavities *l* will cover the whole three of their respective ports, *i i' j*, and the said valves are so set that when the movable seats are in the position represented in Fig. 1 and black outline in Fig. 2 the said valves will cover and admit steam to the two inner ports, *i i*, as will be seen by reference to the right-hand end of the chest in Fig. 1, each in its turn, and always bring the other one into communication with its respective exhaust-port *j*, and that when the said seats are in the position shown in Fig. 3, the said valves will effect the induction of steam to and from the two outer ports, *i' i'*. In the last-mentioned position of the movable seats the opening of the ports to the steam is effected by the movement of the valves away from their respective ends of the steam-chest, and in the first-mentioned position of the said seats it is effected by the movements of the valves toward their respective ends of the chest, and hence the direction in which the rotary motion of the engine is produced depends upon the position of the valves. It will therefore be understood that it is only necessary to shift the

movable from one to the other of the two positions described to instantly reverse the direction of the rotation.

By bringing the movable seats to positions midway between those described, so that both ports *i i'* in each are brought within the range of motion of the valves, so that neither will be uncovered when the engine is stopped, and as in this position of the seats both ports *j j'* in each are partly open to their respective ports *b b'* in the permanent seat *a*, any steam that might be in the cylinder at the time of the valves brought to that position will escape through the exhaust-ports, leaving the piston free.

In setting the valves with "lead," whatever lead is given for running the engine in one direction is also given in running in the opposite direction, without changing from one wrist to another of the valve rock-shaft.

I do not claim, broadly, the employment of movable valve-seats for effecting the reversal of steam-engines; but

What I claim as my invention, and desire to secure by Letters Patent, is

The combination, with two slide-valves, *A A*, of two movable three-ported valve-seats, *F F*, and a system of six ports in the permanent seat, the whole constructed, arranged, and operating substantially as and for the purpose herein set forth.

DAVID B. TRAVIS.
